ROTARY DRILLING RIG

James E. Smith, Pittsburg, Tex.

Application June 22, 1940, Serial No. 341,868

9 Claims. (Cl. 255—22)

My invention relates to a rotary drilling rig, for drilling oil wells, which is hydraulically operated and adapted to conserve time and labor as well as cost of operation and wherein the weight of the drill pipe will be carried by the hydraulic cylinders and hence the use of the usual draw works, draw works engine, the traveling and crown block, etc. will be eliminated and constant proper control of the drill pipe provided and the possibility of drilling an improper or crooked hole prevented.

The invention contemplates a metal derrick composed of lower and upper sections which are hingedly connected and provided with hydraulic lifting cylinders, preferably of different capacities and having telescopically arranged cylinder extensions and sleeves provided with plungers which are operatively connected with the sleeves and are actuated by the pistons of the cylinders; the sleeves being connected with a table housing containing the drill pipe rotating means and pipe holding slips; the table housing being vertically movable in the lower derrick section in which hydraulically operated pipe wrenches are also mounted; while the upper section is provided with the pipe positioning and racking or crane mechanism.

The invention contemplates a plurality of hydraulic cylinders of different capacities, with certain of the cylinders, in order to conserve power, taking care of the "tare" load of the vertically movable table housing, acting as counterbalancing cylinders, while the other cylinders control the drill pipe and may be brought into action in separate pairs as the pipe load or depth of the well increases and vice versa.

The invention also contemplates a specially designed swivel connection, carried by the movable table housing, and connected with the drilling mud supply line which consists of a suitable sized pipe which materially reduces the "mud friction" encountered in the smaller rubber hose at present employed and hence reduces the pump load as well as the maintenance cost; the swivel connection, however, not being required to carry the weight of the drill pipe load which is transferred to the table housing and its large bearings.

My invention also involves hydraulically operated wrenches movably mounted in the lower part of the rig whereby the making up and breaking out of pipe joints is accomplished; the wrench mechanism being vertically movable by a suitable "lift" so as to be positioned adjacent the upper end of the drill pipe and adjacent

the lower end of the pipe section to be added, or removed, and thus eliminates the necessity of hoisting the drill pipe "off bottom" as is the case when a "Kelly" joint is used. This not only saves time, but when "coring," no interruption or joint changing is needed.

My invention further contemplates the use of a fluid motor or turbine for rotating the drill pipe and hence provides a resilient power which tends to prevent crystallization of the drill pipe, as, however, is the case with the present type of rotaries.

The various features and objects and the advantages of my invention will all be readily comprehended from the detailed description of the accompanying drawings wherein:

Figure 1 is an elevation of my improved drilling rig with intermediate portions broken away.

Figure 2 is a sectional plan taken on the line 2—2 of Figure 1.

Figure 3 is a sectional view taken on the line 3—3 of Figure 1.

Figure 4 is a sectional view taken on the offset line 4—4 of Figure 3, with intermediate portions broken away.

Figure 5 is a cross sectional view taken on the line 5—5 of Figure 4, looking in the direction of the arrows and showing the turbine.

Figure 6 is a cross section taken on the line 6—6 of Figure 4 and illustrating the wrench mechanism.

Figure 7 is a cross section of the wrench mechanism taken on the offset line 7—7 of Figure 6.

Figure 8 is a perspective view of one of the gripping elements of the wrench mechanism.

Figure 9 is a sectional detail of the pipe control head.

Figure 10 is a detail sectional view taken on the line 10—10 of Figure 3.

Figure 11 is a detail sectional view of a cylinder brake mechanism shown at the right in Figure 4; the view being taken substantially at the hand end of line 5—5 of Figure 4.

Figure 12 is a plan view of one of the hydraulically operated pipe slips with portions shown in section.

Figure 13 is a sectional view taken on the line 13—13 of Figure 12 looking in the direction of the arrows.

Figure 14 is a detail sectional view of the cam slotted shells shown at the top in Figure 13 with the inner elements omitted.

Figure 15 is a plan view of the rig.

Figure 16 is a rear elevation of the upper portion of the rig shown in Figure 15.

Figure 17 is a sectional view taken on the line 17-17 of Figure 15.

Figure 18 is a cross section taken on the line 18-18 of Figure 17.

Figure 19 is a rear elevation of a portion of the crane mechanism.

Figure 20 is a sectional plan taken on line 20-20 of Figure 19 looking downwardly.

Figure 21 is a sectional view taken on the line 21-21 of Figure 19.

My hydraulic drilling rig, as exemplified in the drawings, comprises a derrick consisting of a suitable number of uprights or legs 30 laterally spaced apart and arranged in a somewhat circular relation, as disclosed in Figures 3 and 6, and tied together by suitable bracing and transversely disposed plates of somewhat U-shape as shown at 30^a, see Figures 1 and 3, arranged at predetermined points throughout the height of the derrick. The derrick is provided with a suitable base or platform indicated at 30^b arranged a distance above the ground and the bottom of the derrick is provided with a suitable spider at 30^c which is disposed above the hole or well being drilled.

The derrick is provided with a vertically movable table housing 31 and with a plurality of vertically disposed hydraulic cylinders at 32 which rest on and are secured to the derrick base. The cylinders 32 at the upper ends are formed to receive the cylinder extensions 32^a which extend to the top of the derrick and are suitably secured to the bracing plates 30^a by flanges 33, see Figure 3. Cylinders 32 are provided with pistons or plungers 34 provided at their bottoms with plunger-heads 35; the plungers 34 (which are of considerable length) are adapted to extend into the cylinder extensions 32^a when made to travel upwardly; and the cylinder extensions are lengthwisely slotted on the sides disposed toward the center of the derrick for passage of the ribs 36 whereby the plungers 34 are operatively connected with the upper ends of the outer shells or sleeves 37, thus causing the sleeves 37 to slide lengthwisely of the cylinder 32 and the cylinder extensions 32^a when the plungers 34 of the cylinders and their extensions are actuated by the power medium in cylinders 32. The sides of the sleeves 37 disposed toward the frame-work of the derrick are slotted lengthwisely for passage of the flanges 33—whereby the cylinder extensions 32^a are maintained in place—thus permitting the sleeves 37 to move vertically.

The table housing 31 is preferably provided with upstanding cylindrical bosses 31^a (see Figure 4) in which the lower ends of the sleeves 37 are secured so that the table housing 31 is raised or lowered as the sleeves 37, by reason of their connection with the plungers 34, are made to slide up or down on the cylinders 32 and the cylinder extensions 32^a; it being understood that the plungers of all cylinders are connected to their outer sleeves (six cylinders being shown in Figures 3 and 5) and the cylinders preferably arranged at opposite sides of the vertical median line of the derrick, namely two cylinders 32 and a counterbalancing cylinder 32^b on each side; each of the three cylinders preferably being of different capacity.

The four cylinders 32 at their lower ends receive the operating pressure fluid medium through connections 38 which connect with the pressure medium tanks 39 (see Figures 6 and 1), while the two smallest or counterbalancing cylinders 32^b, by means of pipes 40, are connected

with pressure tank 41 (see Figure 2). The small cylinders 32^b are employed to overcome the tare weight of the table housing 31 and its movable connections and act in the nature of a counterbalance. Water is preferably used as the pressure medium for the cylinders; the fluid in tanks 39 and 41 being placed under pressure by means of a suitable pump, connected at 42 (Figure 2).

The slush pump on the rig will not be in operation during the changing of the pipe, namely when the pipe is being withdrawn, consequently it can be flushed clean of mud and can be used to pump clean water into the hydraulic system of this rig—or a separate clear water pump could be used to supply the necessary fluid pressure.

The supply lines for the cylinders are preferably provided with a safety control consisting of a lever 43 connected with valve 44; the lever 43 being connected with a link 45 which is connected to the bottom of a vertically disposed rod 46 which passes through a square or non-circular opening in lobe 31^b secured to table housing 31 (see Figure 2); the rod 46 is pivotally supported at its top and bottom on the derrick frame and the rod adjacent its upper end and lower end is provided with twists or spirals 46^a (Figure 1) which cause the rod 46 to twist or turn when the lobe 31^b of the housing 31 engages the spiral portions adjacent the upper and the lower ends of rod 46.

The rotation of the rod 46 actuates link 45, lever 43 thereby either closing or opening valve 44, as well as valve 47 whose lever 48 is connected with link 45 by link 49. Valve 44 controls the pressure medium supply for the smaller or lifting cylinders identified as 32^c (Figure 2) while valve 47 controls the pressure medium supply of the largest cylinders 32; and the medium supply to the counterbalance cylinder 32^b flowing through pipe 40 is also automatically controlled by valve 50 whose lever, by means of link 51, is connected with link 45 and hence the flow of pressure medium to all cylinders is automatically controlled during the travel of the table housing 31.

The housing 31 is provided with a fluid operated turbine 52 arranged beneath the cover plate 53 with a central opening for receiving the drill pipe controlling mechanism and the drilling fluid. The fluid for driving the turbine is introduced by pipe 54, leading from a source of pressure supply and the fluid take-off from the turbine is shown at 55 (see Figure 5). The fluid or drilling mud employed in the drilling operation is conveyed by means of line 56 (which is preferably provided with a swinging joint 56^a) to a swivel connection 57 mounted in the housing 31 and rotated by the turbine 52.

The swivel connection 57 is preferably provided with a non-circular top and with a cone-shape lower end 57^a as shown in Figures 4 and 5 and is locked to the rotor 52 by means of sliding cleats 57^b which are held in locking position by a spring 57^c. The bottom of the swivel connection 57 terminates in a hollow spindle portion 57^d having a tapered threaded portion 57^e which screws into the upper internally threaded end of the drill pipe 58; the connection 57 and its spindle portion 57^d being formed to convey

the drilling mud into the drill pipe.

In order to suitably brace the upper ends of the vertically movable sleeves 37 I provide the annular bracing 59 (Figure 4) provided with cylindrical sleeve portions which encircle the slideable sleeves 37 and are connected thereto and

this bracing 59 holds all of the sleeves 37 in proper alignment and moves vertically with the sleeves 37.

The turbine 52 is rotatably supported on the base of the table housing 31 by antifriction bearings shown at 61; and the base of housing 31 is shown provided with an annular baffle 62 which extends into an annular slot in the lower side of the turbine; the baffle 62 being disposed intermediate of the bearings 61 and the central hole in the bottom of the housing 31 to prevent passage of the lubricating oil into the hole of the housing.

The bottom of the derrick, namely in the spider 30^c, (Figure 1) and the movable table housing 31 are provided with hydraulically operated slips, (Figures 12, 13 and 14) which are identical in construction and operation, whereby the drill pipe and drill pipe sections are firmly held in position against movement; the slips in the spider at the bottom of the derrick being intended to hold the drill pipe in the well, when the slips in the table are not in pipe gripping position, namely while the pipe joints are being made or broken, while the upper slips in the housing hold the pipe section when the pipe is being lifted or lowered into the well; the upper slips merely being employed at the time mentioned.

One set of these slips is shown in Figures 12, 13 and 14 and consists of segmental cone-shape elements or blocks 63 arranged in an annular manner as shown in Figure 12 and adapted to fit into the cone-shaped bushing 64 arranged in rotor 52, which constitutes a support for the swivel connection 57, as shown in Figure 4.

The segmental blocks 63 are each controlled by a link 65; the upper ends of the links being pivotally connected with a ring 66 which is rotatable in member 67 which is of C-shape or channel formation in cross-section, see Figure 13, and is provided with trunnions 68 at opposite sides; member 67 being adapted to move upwardly and downwardly. The trunnions 68 extend through the oppositely disposed ogee slots 69 formed in the concentrically arranged cylindrical shells 70, 71 which have rotative relation with each other and are rotatably mounted on the table housing cover plate 53; the slots 69 in the inner shell 70 being disposed upwardly in one direction while the slots 69 in the outer shell 71 are disposed upwardly in the opposite direction, with the upper ends of the slots given a slight drop so that when the trunnions 68 reach the extreme upper ends of the slots the shells 70, 71 will be held against rotative movement until extra rotative power has been applied to release the trunnions from this safety lock position. The shell 71, in Figure 12, is shown provided with an ear or lobe 71^a to which the plunger 72 of hydraulically operated cylinder 73 is secured; the cylinder being horizontally disposed and mounted on the housing cover plate 53; the cylinder is preferably of the double acting type so as to rotate the shell 71 in opposite directions.

As is apparent from the construction illustrated in Figure 14, rotation of the shells in opposite directions will cause the trunnions 68 to ride upwardly as the upper ends of the oppositely disposed slots come into registering relation and thus induce members 66, 67 to move upwardly in shell 70 and thereby lift the slip blocks 63 (through the medium of links 65) out of the cone-shape bushing 64 and hence out of holding engagement with the pipe shown at 58; while rotative movement of the shells in the opposite

direction will cause the lower ends of the ogee slots in the two shells to be brought into register with each other and consequently induce the trunnions 68 to travel downwardly and cause the slip blocks 63 to move into pipe wedging relation.

It will be understood that when a section of pipe is to be added to the drill pipe, the slips in the spider at the bottom of the derrick (not shown but identical with the construction described) are forced into gripping engagement with the exposed portion of the drill pipe. At this time the swivel connection 57 is disconnected from the drill pipe 58 and the table housing 31 with swivel connection 57 raised sufficiently to permit the pipe section to be positioned in the derrick underneath the table housing 31. The pipe section is then screwed to the drill pipe 58, the table housing is then lowered until the threaded portion 57^a of the swivel connection can be screwed into the upper end of the pipe section just added as shown in Figure 4; the slip mechanism in the housing 31 being merely employed when the entire drill stem is removed from or lowered into the well, as for example when the drill is to be replaced. After the housing with the swivel connection 57 has been lowered as stated, the added section is then screwed to the drill pipe by suitable wrench mechanism now to be described. The hydraulically operated pipe slip mechanism described is used when lowering or raising drill pipe and is not in use during drilling operation but is replaced by the swivel connection 57 heretofore described.

The wrench mechanism is mounted at the base 35 of the rig beneath the table housing as shown in Figures 4 and 6 and consists of suitable vertically spaced housings one above the other generally indicated at 74, 74^a; the horizontal positions or elevations being controlled by plunger 75 of a 40 hydraulic cylinder 76. The housings 74, 74^a are elongated and extend transversely toward one side of the derrick as shown in Figure 6 and the outer ends apertured for passage of a non-circular vertically disposed shaft 77 which is rotated 45 by means of a fluid motor 78 (see Figure 1); the housings, however, being slidably connected with shaft 77 to permit the raising and lowering of the housings with the contained wrench mechanisms.

50 The outer end of housing 74 is provided with a small sprocket 79 which has a non-circular hole for passage of the shaft 77 therethrough and is adapted to be driven by shaft 77. The sprocket 79 drives an endless sprocket chain 80 which in 55 turn drives the large sprocket 81 which is disposed about and is secured to the cam members or castings 82 provided with arcuate grooves 83 (see Figure 6) and these grooves receive the pins 84 arranged at the outer ends of the pipe gripping elements 85, preferably composed of steel blocks as shown in Figure 8; the elements 85 being slidably mounted and controlled by a pair of concentrically arranged steel rings 86, 87 between which suitable oil packing is placed. The 60 steel rings 86, 87 are secured at top to plate 88; top plate 88 being rotatably or loosely mounted on housing 74, while bottom plate 89 is slidably mounted on the bottom outer plate 90 which is mounted on housing 74; the plates 88 and 89 65 maintaining the spaced relation between rings 86 and 87 which in turn guide the elements 85 in their reciprocating or sliding movements.

In order to induce the elements 85 to move inwardly (from the retracted position shown in 70 Figures 6 and 7) into pipe gripping relation

with the upper pipe section 58, I provide a brake for the top plate 88, consisting of a small hydraulic cylinder 91 (see Figure 7) provided with a brake-shoe plunger 91^a which is adapted to engage the perimeter of plate 88 and to hold the latter against rotative movement until the elements 85 have been brought into pipe gripping position, at which time the brake will be released and plate 88 permitted to move with the lower plate. I prefer to employ a pair of cam members 82 in each wrench; one cam member being provided with the cam grooves 83 on its upper face, while the other member has the cam grooves 83 on its lower face, at which time the gripper blocks 85 are reversed so that the pins 84 are disposed upwardly into the cam grooves 83, as shown in Figure 7, thus positioning the gripper blocks in different horizontal planes and avoiding pressure on the drill pipe being exerted in the same plane.

In order to return the top plate 88 and rings 86, 87 to normal position, and hence to retract the elements 85, after the driving power on the sprocket chain 80 has been released. I show the top plate 88 provided with small lugs 88^a operatively engaged by springs 92 (Figures 6 and 7).

The gripper blocks 85 at their inner ends are concaved and provided with a pair of semi-circular sockets, extending from top to bottom of each block or element, to receive the cylindrical steel bars or rods 85^a provided with exposed serrated surfaces, see Figure 8; the gripping bars or rods which are endwise inserted in their sockets are rotatably held in place by plates 85^b secured to the top and bottom faces of the gripper blocks; the spherical socket connection between the serrated rods and the gripper blocks compensate for differences in pipe diameter.

In order to aid motor 78 either in screwing up the pipe sections to obtain a tight point or in breaking or unscrewing tight joints between the pipe sections when the latter are being withdrawn, I provide an auxiliary hydraulic cylinder 93 whose rear end is pivotally mounted in the wrench housing 74 to permit the cylinder to swing toward opposite sides of the housing; the cylinder 93 being provided with a plunger 94 whose outer end terminates in oppositely disposed hook-like fingers which are adapted to enter the links of the sprocket chain 80. The cylinder 93 is preferably operated by oil under pressure; the cylinder 93 being supplied with the pressure medium by tube 95 connected with a source of pressure medium. Cylinder 93 is shown swung to the left in Figure 6 with plunger 94 in engagement with the sprocket chain 80 and exerting a pushing force on the chain toward the large sprocket wheel 81, which causes the chain to move in counterclockwise direction and hence in pipe unscrewing direction, thus assisting motor 78 and avoiding excessive strains on shaft 77 during initial unscrewing when greater power is required. In the event additional power is needed for effecting a tight joint when a pipe section is being added to the drill pipe beneath, cylinder 93 is swung toward the right in Figure 6—plunger 94 having been retracted—and the adjacent finger of plunger 94 is placed into engagement with the portion of the sprocket chain 80 at the right hand side of the wrench housing 74, thus causing plunger 94 to exert a pushing force on chain 80 toward large sprocket 81 in clockwise or screwing direction. It will be understood that cylinder 93 is moved to an intermediate position in the

housing during the normal screwing or unscrewing operations of the top wrench mechanism.

The upper wrench mechanism just described is intended to rotate the upper pipe section 58 either during addition or withdrawal of pipe sections to the drill pipe therebeneath.

During the screwing and unscrewing operations it is, of course, necessary to firmly hold the drill pipe against rotation which is accomplished by the bottom wrench mechanism mounted in the housing 74^a which is supported in spaced relation with the upper wrench housing 74 by a nut 96 on the threaded upper end of plunger 75 of cylinder 76, see Figure 7.

The bottom wrench housing is anchored on drive shaft 77 by bushing 97 loosely slidable on shaft 77 and rotatable in housing 74^a. The bottom wrench mechanism is substantially similar to the upper wrench mechanism insofar as the cam castings 82 and gripper blocks 85 are concerned, but is not provided with sprocket 81 and sprocket chain 80. The housing 74^a has a rotatable top plate 98 to which the rings 86, 87 are secured and top plate 98 is provided with a laterally disposed lug 99 controlled by the pistons of the hydraulically operated cylinders 100 arranged on opposite sides of the lug 99 and secured to the housing 74^a. Outward movement of the piston of one cylinder 100 causes plate 98 to rotate in a direction which causes gripper blocks 85 (which are similar to those previously described) to move into pipe gripping position, while outward movement of the plunger of the other cylinder rotates the plate in a direction which induces retraction of the gripper blocks 85 (see Figure 6).

In practice, after the wrench mechanism has been elevated to position by the plunger 75 of cylinder 76 where the upper wrench is coincident with the lower end of the upper pipe section or thribble and the lower wrench is coincident with the upper end of the drill pipe or pipe in the well, the lower wrench is then placed in gripping relation with the drill pipe or lower pipe section before the upper wrench is rotated in order that the twisting strains be not transmitted to the lower or drill pipe section. The wrench mechanism during drilling operation is lowered to the bottom of the rig with the drill pipe disposed through the openings in the top and bottom plates of the wrench mechanism but with the gripper blocks 85 retracted.

The hydraulic cylinders and fluid motors heretofore described, viz. the cylinders for operating the pipe slips and wrenches are all preferably operated by oil from a common source of oil under pressure.

In Figures 15 to 20, I illustrate the crane mechanism for positioning the pipe sections or thribbles to be added to the drill pipe and for racking the sections or thribbles that have been unscrewed from the drill pipe.

One of the uprights or legs 38 at the rear of the derrick has a vertically disposed tubular shaft 101 mounted therein (see Figure 15) which extends to the bottom of the derrick and is rotated by a suitable two-way fluid motor (not shown) and the leg 38 at its upper end and on one side is provided with a longitudinally disposed opening (as shown in Figure 17) through which the toothed perimeter of a gear 102 extends; the gear 102 being secured to shaft 101 to rotate therewith. Gear 102 meshes with the internal teeth of a sprocket wheel 103 which drives the traveling pipe carrying crane 104 (see Figure 19) through the medium of sprocket chain 105; the crane 104

rides on a frame 106 suitably supported on the derrick and disposed about the upper part of the derrick, as shown in Figure 15. Sprocket 103 is rotatably supported in place by a suitable collar on the leg 30, as shown at 107 in Figure 17; and this leg 30 at a predetermined distance beneath sprocket 103 is provided with a second sprocket 108 which also has internal teeth with which gear 102 is intended to mesh when shaft 101 is lowered; the slot or opening in the leg 30 permitting gear 102 to move downwardly into mesh with the internally toothed sprocket 108.

Sprocket 108 controls an endless chain 109 which merely travels in a direction transversely of the derrick and is connected as at 109^a (Figure 16) with the crane carrying frame or track 106, which is slidably mounted on the supporting frame 110, and shifts the track 106 toward and away from the vertical median line of the derrick; chain 109 travels beneath chain 105 about sprockets located at 111 (the sprocket for chain 109 being beneath the sprocket for the upper chain) and 112 in Figure 15; while upper chain 105 travels about a sprocket located at 111, sprockets at 113 and a sprocket at 114; the upper sprocket at 111 for chain 105, sprockets 113 and sprocket 114 are secured to the movable frame or track 106.

As previously described, gear 102 is merely brought to register with internally toothed sprocket 108 when it is desired to move the upper frame or track 106 across the top of the pipe holding racks 115 arranged at the side of the derrick so as to position the pipe carrying means (to be described) above the respective rows of up-ended pipe sections shown at 58.

The crane 104 is provided with depending rods or supporting bars 116, 116 provided at their lower ends with a tie plate 117, while the upper ends of the rods each have a gripper wing 118, 118^a slidably and rotatably mounted thereon; the wings being yieldingly supported and moved to open or normal position by light springs 119 coiled about the supporting rods 116; the wings being preferably of comparative width and their inner faces provided with serrations or pipe gripping surfaces.

Mounted between the rods or bars 116 and suitably secured thereto is a vertically disposed hydraulic cylinder 120 provided with a piston 121 whose upper end has a substantially annular hood 122 secured thereto to move vertically with the piston. The hood 122 is disposed about the supporting rods 116, Figure 20, and at its inner side, namely the side disposed toward the pipe rack is provided with a cut-out tapering toward the bottom as shown at 122^a with one side of the cut-out arranged at a greater degree than the other side of the cut-out (see Figure 19). The supporting rods 116 carry a self closing valve 123 arranged in a pressure medium supply line 124; the valve also communicates with one end of the cylinder 120 and is provided with tripper or actuating arm 125 preferably provided with a forked outer end, as shown in Figure 20.

When the pipe carrying crane has been positioned where the tripper arm 125 comes into contact with a section of pipe, valve 123 will be opened and pressure fluid admitted to cylinder 120, causing its piston 121 and the hood 122 to be forced upwardly about the gripper wings 118, 118^a with the wings disposed through the cut-out 122^a in the hood. As the hood 122 moves upwardly the wings 118, 118^a will be forced toward each other, by the wedge shaped cut-out, into

pipe gripping position. Wing 118 normally opens outwardly to a greater extent so as to engage a pipe section slightly in advance of inside wing 118^a especially when removing a pipe section from the rack, thus enabling the wing 118 to move between adjacently placed pipe sections before wing 118^a is in complete contact with the pipe section which would prevent proper closing movement of the wings. After the pipe section has been removed from the gripper wings, the tripper valve is returned to closed position by suitable means, as for example by a coiled springs 125^a, see Figure 21.

In Figures 1, 2, 3 and 9, I illustrate the pipe controlling and positioning mechanism whereby the pipe sections, brought from the rack by the traveling crane and its gripper mechanism, will be vertically centered with the well or drill pipe; or the respective pipe sections after having been unscrewed may be swung away from the derrick center and into the path of the gripper mechanism carried by the crane and thereby placed in the pipe rack.

A pair of pipe controlling and positioning mechanisms are preferably employed with one of the mechanisms arranged adjacent the upper end of the derrick and above the path of the traveling crane and the other located adjacent the lower end of the derrick.

The controlling mechanism at the upper end of the derrick consists of an arm 126 whose one end is swiveled in a block 127 (see Figure 10); arm 126 and block 127 being vertically slidably on the vertically disposed square rod 128. Block 127 has a tapped hole to receive the threaded upper end of a vertically disposed screw-rod 129 which also extends to the bottom of the derrick and is pivotally supported at its top and bottom on suitable supporting brackets secured to the derrick; the screw-rod 129 may be controlled or rotated by a suitable two-way fluid motor. Rotation of screw-rod 129 causes the block 127 and the arm 126 to travel vertically and to slide lengthwise of the square or non-circular rod 128, to properly position the pipe positioning mechanism, and the arms of both upper and lower control mechanisms may then be manually swung horizontally toward or away from the vertical center of the derrick.

Screw-rod 129 is enclosed in a substantially cylindrical shell 130 (open on one side for passage of block 127 therethrough) which is bolted or otherwise suitably secured to an adjacent leg 30 of the derrick, namely to the foremost leg at the left of the derrick as viewed in Figures 1, 2 and 3; and because of the length of screw-rod 129, it is preferably braced or rotatably secured to the shell 130 by suitable collars as at 131; block 127 at its rear side being vertically slotted to permit the block to travel past the collar connection with the outer shell 130; while the open side of the outer shell 130 is preferably provided with leather aprons or flaps 130^a (see Figure 3) to prevent entrance of mud and dirt to the screw-rod 129; the free edges of the aprons being in lapping relation to permit passage of the block 127.

The outer end of upper arm 126 has a dome-shaped head 132 (consisting of an upper and a lower portion which are screwed together) swiveled thereon by means of a trunnion or pin 133 secured to the head and disposed through an opening in the end wall of arm 126; the outer end of the pin 133 being threaded and provided with a nut 133^a (Figure 9); the connection be-

tween head 132 and the arm 126 permits the head to swing transversely of the arm.

The dome-shaped head 132 terminates at top in an upwardly disposed cylinder portion 132^a (see Figure 9) connected at top with a pressure fluid supply line 134; and cylinder portion 132^a receives the plunger portion of a reciprocatingly mounted member 135. The mouth of member 135 is provided with a plurality of annularly arranged serrated fingers 136 which are pivotally secured adjacent their lower ends projecting namely at 137, with their lower ends projecting beyond the pivot points, while the upper ends of fingers 136 are normally forced inwardly by means of springs 138.

The projecting lower ends of the fingers 136 extend into the path of and are controlled by the cam surface 139 formed at the lower open end of head 132; the cam surface or portion 139 being provided with an upwardly disposed annular extension 139^a which enters a vertical slot 135^a formed in the bell-shaped wall of member 135 and properly guides member 135 in its reciprocating movements. The enlarged or cam portion 139 of the head 132 is provided with an annular chamber 140 immediately beneath the lower end of member 135 (which is preferably provided with an annular gasket 141) and receives a pressure fluid from the pipe or hose 142 (leading from a source of pressure fluid supply). When the pressure fluid enters chamber 140, member 135 will be forced upwardly, moving the lower extended ends of the fingers 136 out of contact with the cam surface 139, permitting the springs 138 to force the upper ends of fingers into gripping relation with the upper end of an up-ended pipe section. The arm 126 is then swung about its pivotal connection with block 127 until the head 132 with the depending pipe section has either been swung into vertical alignment with the central opening in the table housing, as shown in Figure 1 (if the pipe section is to be added to the drill pipe), or has been swung outwardly into proximity with the path of the traveling crane and its pipe grasping mechanism previously described, as indicated in dotted lines in Figure 15 (if the pipe section has been unscrewed from the drill pipe and is to be placed in the pipe rack).

After the arm 126 with head 132 has been brought to the desired position where the pipe section is to be released, the pressure medium to chamber 140 is shut off and allowed to flow through hose 134 into the cylinder portion 132^a of the head 132, thereby forcing member 135 downwardly until the extended lower ends of the fingers 136 engage the cam surface 139 which causes the extended lower ends of the fingers to move inwardly or toward each other and forces the upper ends of the fingers outwardly or out of holding relation with the upper end of the suspended pipe section. It will be understood that the head 132 is brought down into contact with the upper end of a pipe section by rotating screw-rod 129 in proper direction and after the pipe section has been positioned the head 132 is elevated above the pipe section by turning screw-rod 129 in the opposite direction. Member 135 is loosely mounted in head 132 so that member 135 may rotate with the suspended pipe while the latter is being screwed onto or off a lower pipe section; and head 132 is swiveled on arm 126 to permit the mouth of the head and member 135 to be properly aligned or positioned to receive the elevated end of a pipe which is to be raised from

the ground and either positioned for screwing onto the drill pipe or to be placed in the rack.

In view of the length of a thribble of pipe (namely three pipe sections of approximately 30 feet each in length) it would be rather difficult to hold the pipe suspended from the head 132 against swaying movement and also to center the lower end with the central hole in the table housing and the mechanisms mounted thereon. I therefore provide a swingingly mounted arm 126^a adjacent the lower end of the derrick, see Figure 1. Arm 126^a is hingedly connected at 143 to a block member similar to the block member 127 of the upper arm and previously described; arm 126^a being hingedly connected as just mentioned so it may be swung upwardly out of the way. The lower block member is similar in general construction to the block member 127 of the upper arm except that the opening through the lower block is not threaded and loosely fits on rod 128 and hence does not travel vertically when rod 128 is rotated.

The upper head 132, on the side disposed toward the derrick when the head 132 is swung inwardly, is also preferably provided with a somewhat U-shape element 132^b (Figure 15) provided with serrations or teeth and may be used when adding or taking out a single joint of drill pipe; the device holds the single joint in place for attachment to the threaded end 57^a of the swivel connection and is swung away when the joint is in proper position.

The lower arm 126^a has a pair of hook-like gripping fingers 144 pivotally mounted on the outer end and these fingers are held in open position by a suitable spring 145 secured to a lug or projection on the arm 126^a. Mounted on the arm 126^a is a fluid operated cylinder 146 (pressure fluid being introduced by tube 147) whose piston 148 has a pair of links 149 pivotally connected thereto while the outer ends of the links are pivotally connected to the fingers 144. The spring 145 not only separates the fingers 144 into the open position shown in Figure 3 but also retracts the piston 148, after the pressure medium in cylinder 146 has been spent. With the noncircular rod 128 extending through the upper arm holding block 127 and the lower arm holding block 127^a, it is evident that the two arms will be simultaneously positioned and in vertical alignment, so that when a pipe section is to be introduced or lifted out of the way by the lifting head 132, heretofore described, the lower arm 126^a will be in position where its fingers 144 can encircle the lower end of the pipe section upon admitting pressure fluid to cylinder 146, forcing its piston outwardly, causing the fingers to close about the pipe section. Arm 126^a is substantially of the same length as the upper arm 126 and both have a common axis and consequently the pipe section will be held in a vertical plane and in alignment with the hole in the table housing and the pipe slip mechanism mounted thereon. As block 127^a of the lower arm has a smooth non-threaded connection with the lower end of rod 128, the lower arm does not move up or down when screw-rod 129 is rotated to adjust the horizontal plane of the upper arm 126.

In view of the height of the derrick and to facilitate its shifting or handling, the derrick is preferably made in sections and the sections hingedly connected together; the lower section being provided with the table housing and lift cylinders and the upper section provided with

the traveling crane and upper pipe positioning mechanism.

The two sections are shown hingedly connected at the rear side of the derrick as shown at 150 which allows the two sections to fold into parallel relation.

The lower section of the derrick adjacent its upper end is shown provided with a pair of hydraulic cylinders or jacks 151, 151, see Figure 1, secured on the rear legs 30 of the lower section; the jacks being operated by a fluid under pressure received by means of a pump from a suitable source of supply.

In order to hold the table housing 31 and its various attachments at any desired point against vertical movement in the event of an emergency, such as leaks or accidents, I provide braking mechanism operable from the table housing and consisting of a brake band 152 provided with a suitable fibre lining 153; the band being located within the outer shell 37 to which one end of the split brake band 152 is immovably secured as shown at 154 in Figure 11, while the other end of the band is controlled by a pawl 155 disposed laterally from the rotatable brake rod 156 and extending through a slot in the outer shell 37. The brake mechanism is preferably applied to the two large compression cylinders, the one being at the left and toward the rear of the derrick, while the other is at the right and toward the front of the derrick, as viewed in Figures 3 and 5.

The invention permits the use of a derrick of less height; with the weight of the traveling table housing, its appurtenances and the respective pipe sections being carried by hydraulic cylinders preferably of different sizes to take care of differences in load; and wherein the respective pipe sections are properly positioned for attachment to the drill pipe. After the initial pipe section with attached drilling tool has been driven substantially to the limit of its depth and a single pipe section is to be added, the pipe positioning mechanism 132 is lowered to receive the end of the pipe section in the U-shape element 132^b; the mechanism 132 is then elevated, through actuation of means heretofore described, so as to suspend the pipe section therefrom, at which time the lower arm 126^a and its gripping fingers engage the lower end of the pipe section; the two arms being then swung inwardly toward the center of the derrick beneath the elevated table housing where the lower end of the pipe section will be held in position to screw into the upper end of the drill pipe and the upper end of the pipe section positioned to receive swivel connection 57. The pipe section, by means of the wrench mechanism, is then screwed onto the threaded portion 57^e; the table housing then lowered and the lower end of the added pipe section screwed into the drill pipe and the drilling operation resumed, at which time arm 126 and arm 126^a are swung out of the way.

In instances where the entire drill stem is to be removed (for example to change the bit), the wrench mechanism breaks the drill stem from its connection with the swivel connection; said connection is removed and the slip mechanism (Figure 13) is substituted therefor in the rotor of the table housing; the table housing is then lowered sufficiently for the slips to engage the pipe (the load up to that time being carried by the lower set of slips at the bottom of the derrick) and after being placed in gripping position, the housing is then lifted by means of the hydraulic cylinders to its maximum elevation, at which time

the lower slips are again brought into gripping position; the table housing is then lowered to the bottom in order that the set of slips carried by the table housing may engage the drill stem and is raised again to a point high enough to break out a thribble with the wrench mechanism. After the drill pipe joint is broken (the upper end of the thribble being held by the dome-shaped head 132) the wrench mechanism is lowered and the table housing with its set of slips is also lowered to permit the slips to again hold the drill pipe. As soon as the table housing passes beneath the joint that has been broken, then arm 126^a is attached to the lower end of the thribble and the thribble is then swung outwardly where the traveling crane mechanism can engage the upper end of the thribble, at which time the grip of mechanism 132 is released and mechanism 132 is raised out of the way; the thribble then carried by the crane mechanism and placed in the racks shown in Figure 15.

When the pipe is to be replaced, the operations as set forth are reversed.

During drilling operation, the weight of the drill pipe is carried by the pressure fluid in the cylinders, which pressure is set to maintain the desired amount of weight on the bit; it being understood, of course, that the derrick is suitably anchored in place by proper guy rods or wires, as indicated in Figure 1.

The particular embodiment of the invention shown in the drawings may be modified in certain respects without, however, departing from the spirit of my invention as defined in the appended claims.

What I claim is:

1. A rotary drilling rig of the character described comprising a derrick composed of a plurality of vertically disposed uprights arranged in substantially semi-circular spaced relation and secured together by a plurality of vertically spaced tie-members, vertically disposed hydraulic cylinders arranged at opposite sides within the derrick and each provided with a piston; vertically arranged cylinder extensions at the upper ends of the cylinders; a plunger connected to each piston and slideable in each cylinder and cylinder extension; tubular sleeve members slideable on the cylinders and said cylinder extensions with their upper ends secured to said plungers; a rotor carrying table housing provided with a pipe receiving opening therethrough, said housing being secured to the lower ends of the tubular sleeves so as to travel vertically therewith; a swivel connection removably seated in the table housing opening in operative relation with the rotor so as to rotate therewith, the lower end of said swivel connection being adapted to effect operative relation with the drill pipe therebeneath; a fluid supply line for the swivel connection; a source of power medium supply for said rotor; and a pressure medium supply for said cylinders.

2. A rotary drilling rig of the character described comprising a sectional derrick composed of vertically disposed members arranged in substantially semi-circular spaced relation secured together by a plurality of vertically spaced tie-plates, the derrick sections being arranged one above the other and hingedly connected together to permit the sections to fold into parallel relation; power means whereby the upper section is controlled; a rotor carrying table housing with a pipe receiving opening movable vertically in the lower derrick section; vertically disposed hy-

draulic cylinders with reciprocable pistons in the lower derrick section arranged on opposite sides of the table housing; vertically movable means at the upper ends of the cylinders connected with the housing and adapted to be controlled by the pistons of said cylinders; and a pressure medium supply connected with the lower ends of said cylinders.

3. In a rotary drilling rig of the character described, a derrick provided with a vertically movable table housing provided with a pipe receiving opening; a rotor mounted in the table housing concentric with said opening; a swivel connection adapted to seat in said opening to be rotated by said rotor and to effect operative relation with the end of a pipe beneath the housing; a fluid supply for operating said rotor; and means whereby said table housing is made to travel vertically in the derrick.

4. In a rotary drilling rig of the character described, a derrick provided with a vertically movable table housing having a pipe receiving opening disposed vertically therethrough; hydraulically operated rotor mounted in said table housing; a swivel head disposed through said opening, the lower end of said head being adapted to screw into the upper end of the drill pipe therebeneath; means whereby operative relation between the rotor and said swivel head is effected and the latter with the attached drill pipe rotated; and means whereby the table housing may be moved vertically.

5. A rotary drilling rig of the character described comprising a derrick provided with a vertically movable table housing having a pipe receiving opening disposed vertically therethrough; an hydraulically operated rotor mounted in the table housing concentrically with said opening; a swivel head disposed vertically through said opening and through said rotor, with its lower end adapted to effect controlling engagement with the upper end of a vertically disposed pipe section therebeneath; means whereby a driving relation between said rotor and said swivel head may be effected and the weight of the depending pipe supported by the table housing through the medium of said rotor; means whereby the table housing may be moved vertically; and brake mechanism operatively intermediate of the table housing and said means whereby the table housing may be held against downward movement.

6. In a rotary drilling rig, a derrick provided with a plurality of vertically arranged cylinders and pistons arranged at opposite sides within the derrick, with cylinders at each side varying in size; a rotor carrying table housing disposed between the cylinders at opposite sides of the derrick; means operatively intermediate the table housing and the pistons whereby the table housing is made to travel with the pistons; counterbalancing cylinders and pistons at opposite sides of the table housing with their pistons operatively connected with the table housing for carrying the tare load; a pressure medium supply connected with said first mentioned cylinders; and a pressure medium supply for said counterbalancing cylinders.

7. In a rotary drilling rig comprising a derrick with a vertically movable table housing, a rotor mounted in the table housing and having a cone-shaped central opening therethrough, a swivel connection for conveying the drilling mud into the drill pipe beneath the table housing and

adapted to be seated in the central opening in the rotor, said connection involving a non-circular top portion with a cone-shaped depending hollow stem portion whose lower end is adapted to screw into the upper end of the drill pipe and spring controlled means arranged in the top portion and adapted to effect holding relation with the rotor, whereby the drill pipe is rotated through the medium of said swivel connection.

8. A rotary drilling rig of the character described comprising a derrick, composed of a plurality of substantially semi-circularly spaced uprights, provided with transversely disposed U-shape tie-plates for securing the uprights together and with a plurality of vertically arranged cylinders of different capacities having reciprocable pistons; cylinder extensions secured to the upper ends of the cylinders; tie means between the cylinder extensions and said tie-plates whereby the extensions are held against movement, the inner sides of the cylinder extensions being longitudinally slotted; combined pistons and plungers slidable in the cylinders and cylinder extensions and provided with longitudinal slots on their outer sides for passage of the tie means between the cylinder extensions and the tie plates; tie means secured to said plungers, disposed through the slots on the inner sides of the cylinder extensions, and secured to said sleeve members; a rotor carrying table housing secured to the lower ends of said tubular sleeve members to travel vertically therewith; a controllable pressure medium supply connected with said cylinders for controlling the elevation of said table housing; and a pair of conduits connected with the table housing for conveying a pressure fluid medium whereby the rotor is actuated.

9. In a rotary drilling rig of the character described, a derrick provided with a vertically movable rotor carrying table housing with a pipe receiving opening; a plurality of vertically disposed hydraulically operated cylinders arranged at opposite sides of said table housing and provided at their upper ends with longitudinally slotted cylinder extensions and having reciprocating pistons; longitudinally slotted tubular sleeves vertically slidable on the cylinders and cylinder extensions, with their lower ends secured to the table housing; tie means disposed through the slots in the sleeves whereby the cylinder extensions are immovably secured to the derrick; tie means disposed through the slots in the cylinder extensions whereby the sleeves are operatively secured to the pistons and made to travel therewith; a pressure medium supply connected with the lower ends of said cylinders; a rotatable rod disposed throughout the path of travel of said table housing and having operative connection with the valves in the pressure medium supply lines of the respective cylinders; means carried by the table housing and operatively associated with said rod whereby the rod is rotated when the table housing reaches predetermined points in its upward and downward travel and the flow of pressure medium to the cylinders is automatically controlled; and a pair of conduits connected with the table housing whereby a pressure medium is delivered to the rotor and the latter operated.

JAMES E. SMITH.
